UNITED STATES PATENT OFFICE.

WALTER A. KRUCK, OF CAMDEN, NEW JERSEY.

PNEUMATIC PIANO-ACTUATING VALVE.

1,249,777.

Specification of Letters Patent. Patented Dec. 11, 1917.

Application filed August 18, 1913. Serial No. 785,315.

To all whom it may concern:

Be it known that I, WALTER A. KRUCK, a citizen of the United States, residing at Camden, in the county of Camden and

5 State of New Jersey, have invented certain new and useful Improvements in Pneumatic Piano-Actuating Valves, of which the following is a specification.

This invention relates to pneumatic piano actuating valves, and the construction and arrangement thereof with reference to the other essential elements. It belongs, more particularly, to piston-operated valves whereby the bellows that set in motion the 10 piano action units are connected with the suction chamber, and it is believed to be an improvement upon the inventions of like nature disclosed in Letters Patent of the United States issued May 21, 1912, No. 1,027,257, and November 26, 1912, No. 1,045,710. The improvement consists in the special construction and arrangement of parts hereinafter described, which are particularly adapted to be cheaply and rapidly 15 manufactured, and being of metal, do not deteriorate with time and exposure.

The special construction and arrangement comprising this invention are shown in the accompanying drawings. Figure 1 represents a side view of a pneumatic located in operative connection with a piano action; a portion of which is also shown. A vertical section of the construction and arrangement of the parts of this invention is illustrated 20 in connection with the pneumatic. Fig. 2 is a side view of the coupling member detached. Fig. 3 is a side view of the composite valve board, and three controlling valves constructed in accordance with this 25 invention are shown attached to the board as usually arranged. Fig. 4 is a vertical cross-section of the valve board, the valves being omitted, and shows the construction thereof. Fig. 5 is a top view of one actuating valve as described. In the drawings and throughout the description the same letter is used to refer to the same part.

Considering the drawing, the tracker A and the note sheet a may be of any selected 30 character. The tube B from the tracker leads downwardly, and horizontally through the valve board, and then turns upwardly and is joined to the nipple C of the lower portion c of the casing containing the piston and valve described below. The lower portion c of the casing, together with the upper

portion D, and the annular coupling member d, are secured to a suitable bed block E by a strap e that straddles the bed block and has its ends made fast by screws as 40 shown to the front board F which supports both the bed block and the casing. In practice, it is advantageous and makes a tighter joint to provide the bed block E with a piece of leather or the like of about the 45 thickness illustrated. The leather piece is referred to by the letter f.

The horizontal board b supports the pneumatic G, which is connected in the usual manner with the piano action g.

Now, consider the construction and arrangement of parts comprising the controlling valve. Its operating piston H, illustrated, is located and fashioned to fit movably within the lower portion c of the casing. The piston rod h passes upwardly through the annular coupling member d, and bears the valve J near the top. The annular coupling member is provided with two encircling shoulders K and k against 50 which the edges of the casing portions c and D abut when the portions are assembled as shown. The portions of the casing and the coupling member are not threaded in practice, but fit somewhat closely together 55 and are sufficiently held in place by friction. The coupling is shown in Fig. 2.

As shown in the drawing, the lower portion c of the casing has an opening L through its side, and the opening L registers with a like opening M through the bed block E, and with a bore or block tube m in the front or supporting board F. The tube m meets the suction channel n, and serves to exhaust the air from above the 60 piston, and, less rapidly, from below it and from the tube B leading to the tracker, by reason of the fact that the piston is intentionally constructed to fit within the casing movably and to permit air to bleed from 65 below it. In other words, the piston is not air tight in the casing. The suction channel n leads, as will be understood, to the customary chamber from which air is constantly taken by the main bellows, and those common devices are not shown in the drawing.

In addition to the shoulders described, the coupling member d is provided with a raised seat N for the valve J. Under regular playing conditions, and as stated, the valve is 70 seated as shown, by the pressure of the outside air above it.

The upper portion D of the casing incloses the valve and its seat, and, it will be observed in the drawing that the upper edge of the portion D is turned inwardly and downwardly, and the portion of the edge thus turned is marked O. The lower edge of the part O is spanned by a relatively narrow cross piece or guide P, and through the middle of the guide P the upper end of the piston rod h passes. That part of the rod which passes through the guide P is, as shown, above the valve J.

It will be now observed from the drawing that the upper portion D of the casing has an opening Q in its side that registers with a like opening R in the bed block E, and with the block tube r in the front board F. The block tube r communicates with the block tube S in the horizontal board b, and the tube S opens into the pneumatic or bellows G which operates the piano action.

In the operation of this invention, as long as the note sheet a covers the tracker duct, the parts remain at rest. The admission of air through the note sheet will force the piston upwardly raising the valve against the lower edge of the turned-down portion O of the upper portion D of the casing, the edge being an upper seat for the valve, and, the pneumatic is placed in communication with the channel n and immediately operates the piano action.

Now, considering Figs. 3 and 4, it will be noted that the part which may be termed the valve board, is a composite piece, and is made up of the front board F upon which the controlling valves are directly secured, and a back board T, with intervening strips U, V, W, and w, arranged lengthwise as indicated in Fig. 3. The arrangement of the strips described results in the lengthwise suction channels such as the channel n.

It will be observed in Fig. 3, that the controlling valves are not only arranged upon the valve board with their axes inclined to the vertical, but that the valves are not placed one directly below another. In other words, the axes of the valves, inclined as stated, are parallel with each other and separated by a small interval. Thus, the middle points of the valves lie in an inclined line. It will be understood also that there are horizontal rows of valves upon the valve board, each valve in the same row being connected with the same suction channel n. In Fig. 3 one valve of each row is shown, and each valve shown is connected with a different channel from that connected with either of the other valves shown. By inclining the valves and placing them in slanting order as illustrated in Fig. 3, it is practicable to save both in length and in width in the construction of the valve board, which is the object sought, and a feature of considerable advantage in this invention.

By inclining the valves, the perpendicular distance on the valve board between the openings L and Q in the valve casing is shorter than if the valves were vertical. Therefore, a saving in width of the board is effected. Again, when the valves are inclined, the straps e that hold them incline to an assumed horizontal line running lengthwise of the board, and do not, as shown, extend along such line to the same distance as if they were not inclined. A saving in the length of the valve board results.

The horizontal board b that is joined to and supports the pneumatic G, does not directly connect with the back board T of the composite valve board, but is joined to the block s, usually square, as shown in Figs. 4 and 5, and of which there may be any desired number. It is customary in practice, after passing the tube B, and its fellows not shown, through the valve board, to run them upward behind the valve board between blocks s, as shown in Fig. 1.

Having now described this invention and explained the mode of its operation, what I claim is:—

1. A valve device, comprising a casing having hollow upper and lower portions provided with side openings, a coupling portion having a central opening and constructed to connect the said upper and lower portions and provided with a valve seat located in the said upper portion of the casing when the portions are connected by the said coupling, the upper portion of the casing being made in one piece and having its upper edge extending inwardly and downwardly forming a valve seat below the top of the casing and above the said seat on the said coupling, a piston movable in the lower portion of the casing, a valve controlling the said seats, and a rod connecting the said valve and piston.

2. A valve device, comprising a casing having upper and lower portions provided with side openings, a coupling portion having a central opening and constructed to connect the said upper and lower portions and provided with a valve seat located in the said upper portion of the casing when the portions are connected by the said coupling, the upper portion of the casing being made in one piece and having its edge extending inwardly and downwardly and diametrically connected by a cross-piece integral with the said edge, the said inwardly and downwardly extended edge forming a valve seat arranged above the said seat in the said coupling, a piston movable in the lower portion of the casing, a valve controlling the said seats, and a rod connecting the valve and piston, the said rod passing through and being guided by the cross-piece.

3. The combination with a plurality of rows of valves, of a valve board having a

number of channels extending lengthwise of the board, the said valves being arranged upon the board at different distances from the longitudinal edges of the board, and each row of valves being connected with a different channel from that connected with either of the other rows of valves.

4. The combination with a plurality of rows of valves, of a valve board having a number of channels extending lengthwise of the board, the said valves being arranged upon the board at different distances from the longitudinal edges of the board, and each valve having its axis inclined to the said edges of the board, and each row of valves being connected with a different channel from that connected with either of the other rows of valves.

5. In a player piano, a vertically disposed board adapted to be positioned in the front of the piano in advance of the hammer actions and having a reservoir adapted to be connected to a source of pneumatic power, said board being free of pneumatic controlling mechanism, banks of pneumatics carried on the rear face of said board and operatively connected to said actions and banks of valvular pneumatic controlling elements mounted on the front face of said board and controlling the passage of air between said reservoir and said pneumatics, said board having ports communicating with said elements and with said reservoir, each of said elements being individually removable from the front face of said board whereby convenient access is obtained to the ports covered by any one of the elements without disturbing the other elements.

6. In a player piano having a series of hammer actions, a unitary structure comprising a board having a compartment adapted to be connected to a source of pneu-

matic power, banks of pneumatics mounted on one face of said board and adapted to be brought thereby into operative relation to said hammer actions, corresponding banks of valvular elements removably mounted on the opposite face thereof, each element controlling the passage of the power from said compartment to one of said pneumatics.

7. In a player piano, a tension box comprising three flat boards each having transverse openings bored entirely therethrough, certain openings in the inner board constituting a vacuum reservoir, certain openings in one of the outer boards communicating directly with said vacuum reservoir and certain other openings in all three boards constituting a passageway through the box and adapted to place a pneumatic in fluid communication with its controlling valvular element.

8. A piano action comprising a tension box in the form of a flat board having a compartment contained therein and adapted to be connected to a source of pneumatic power, a conduit leading from said compartment to one side of the box, said box having a second conduit with one end disposed adjacent the outer end of the first named conduit, and extending through said box to the opposite side, a valvular element containing all the means necessary for controlling the passage of air through said two conduits, said element being demountably affixed to the tension box and covering the outer ends of said conduits.

In testimony whereof I affix my signature in presence of two witnesses.
